Primary Examiner — Mark A Goodwin*Assistant Examiner* — Benjamin M Weeks*(74) Attorney, Agent, or Firm* — Global IP Counselors, LLP(57) **CLAIM**

The ornamental design for a light fixture, as shown and described.

DESCRIPTION

FIG. 1 is a front perspective view of a light fixture in accordance with our new design;

FIG. 2 is a rear perspective view of the light fixture in accordance with our new design;

FIG. 3 is a front elevational view of the light fixture in accordance with our new design;

FIG. 4 is a rear elevational view of the light fixture in accordance with our new design;

FIG. 5 is a top plan view of the light fixture in accordance with our new design;

FIG. 6 is a bottom plan view of the light fixture in accordance with our new design;

FIG. 7 is a right side elevational view of the light fixture in accordance with our new design;

FIG. 8 is a left side elevational view of the light fixture in accordance with our new design; and,

FIG. 9 is a front perspective view of the light fixture in accordance with our new design illustrating a state in which a pole is extended. The broken line showing of environmental structures in the drawings forms no part of the claimed design.
